T. S. Hudson
Hand Stamp

Nº 64320.

Patented April 30, 1807.

WITNESSES:

INVENTOR.

Thos S Hudson

United States Patent Office.

THOMAS S. HUDSON, OF EAST CAMBRIDGE, MASSACHUSETTS.

Letters Patent No. 64,320, dated April 30, 1867

HAND-STAMP.

The Schedule referred to in these Letters Patent and making part of the same.

TO ALL WHOM IT MAY CONCERN:

Be it known that I, THOMAS S. HUDSON, of East Cambridge, in the county of Middlesex, and State of Massachusetts, have invented certain improvements in Hand-Stamps, of which the following is a full, clear, and exact description, reference being had to the accompanying drawings, making part of this specification, in which—

Figure 1 is a perspective view of my improved stamp.

Figure 2 is a longitudinal vertical section through the centre of the same.

Figure 3 is a vertical section through a portion of the casing containing the type-wheels and the shaft by which they are revolved when required to be adjusted.

Figures 4 and 5 are plans of the sides of the type-wheels, upon which are stamped the letters and figures denoting the months and days of the month.

Figure 6 is a perspective view of one of the type-wheels, the side opposite to that bearing the letters or figures being shown uppermost.

Figure 7 is a view of the spindle by which the type-wheels are revolved.

My invention relates to that class of hand-stamps in which circular type-wheels are employed, and more particularly relates to certain improvements in the stamp for which Letters Patent of the United States were granted to B. B. Hill, on the 6th of November, A. D. 1866.

In the patented stamp above referred to, the type-wheels and "dials" which indicate the characters ready for stamping the impression, are made separate and distinct from each other, the "dials" being fitted over the hubs of the type-wheels upon which they revolve. The object of my invention is to simplify the construction of this stamp by dispensing with the dials, and provide a means whereby the revolution of the wheels necessary to effect their adjustment may be performed in a more convenient and expeditious manner; and my invention consists in revolving both of the type-wheels by the spindle upon which they are placed, and also marking upon the sides of the type-wheels the letters and figures to be stamped, and in connection therewith providing the casing with holes for exposing to view the letters and figures on the sides of the wheels corresponding to those on the edges of the wheels ready to impart the impression; and my invention furthermore consists in a swinging or sliding key for locking the type-block indicating the year securely in a position ready for use.

To enable others skilled in the art to understand and use my invention, I will proceed to describe the manner in which I have carried it out.

In the said drawings, A is the base from which rises the bent arm B, in a suitable bearing, C, in which slides a vertical plunger, D, which is made hollow for the reception of a spiral spring, a, the bottom of which rests upon a pin, b, passing through the plunger into its bearing, by which construction the plunger is retained in a position ready for use, as seen in figs. 1 and 2. In the foot of the plunger is secured a shell or casing, E, of the form shown, and provided with a removable plate, F, to allow of the admission of the type-wheels G H, which are revolved by the spindle I, which has its bearings in the front and back of the casing E. The edge of the type-wheel G is provided with the letters indicating the names of the months, while that of the wheel H is provided with the figures indicating the days of the month, and the letters and figures corresponding to those on the edges of the wheels are legibly marked on the sides of their respective wheels, and the particular characters corresponding to those ready to be stamped are exposed to view through the aperture c formed in the removable plate F in the front, and through the aperture d in the back of the casing.

The manner in which the type-wheels are revolved, so as to bring the required date into a position ready to impart the impression, will now be described. The sides of the wheels opposite to those which bear the scales indicating the letters and figures to be stamped, are provided with notches, e, which extend only partially through the thickness of each of the wheels, and the spindle I is provided with a projection, f, which fits within the notches e, by which means either wheel may be revolved when desired by operating the spindle. The wheel H (bearing the figures representing the days of the months) may be revolved, without revolving the wheel G, by the spring g, which surrounds that portion of the spindle I, on the outside of the front of the casing, and serves to draw the projection f into the notches e on the wheel H, the spindle being kept in place within its bearings in the casing by a screw, h. When it is desired to revolve the wheel G without revolving the wheel H, the spring g may be compressed, and the spindle I turned until its projection f is brought into line with a notch, i,

which passes entirely through the side of the wheel H, by which construction the projection f will be disengaged from the notches e in the wheel H, and enter one of the notches e in the wheel G, and revolve it, the spindle I turning freely within the wheel H without causing it to rotate. When the type-wheels are adjusted in their proper position for stamping the desired characters, they are prevented from revolving by the following means: Between the characters on the edges of the wheels are formed notches, k, into which the ends l of the bent springs m catch, and thus retain the wheels when the stamp is adjusted for use, an aperture, n, being made in the side of the casing to allow of this being done. The construction and arrangement of the device for holding the type indicating the year will now be described. Within the front of the casing, immediately under its centre, is formed a recess, o, (see fig. 1,) the sides of which are bevelled inward for the reception of a type-block, K, correspondingly bevelled, and bearing the figures indicating the year to be stamped, which is securely held in place by a key, L, which is pivoted at its upper end around the spindle I, so that when swung into the position seen in section, fig. 2, the front portion P of the key L will come in contact with the front of the type-block k, while a projection, q, fits down upon its top, thereby preventing any lateral or vertical motion. r is a circular recess in the casing, in which the projection q moves when the key L is swung to one side to remove the type-block k; s is a plate which bears the types which indicate the name of the person, place, or thing, the impression of which is to be constantly stamped, and is therefore intended to remain permanently in place, a screw, 8, being employed to fasten it to the lower end of the casing. The interior of this plate s is made hollow, to allow space for the reception of the lower ends of the type-block K, and type-wheels G H, and allow these wheels to revolve freely therein. M is the type-bed, which is loosely pivoted at t to the base A, in order that its upper surface may yield to conform to the surface of the types which are to stamp the impression. N is the inking-ribbon, rolled around the rods u, having their bearings in the centre of the boxes O, and operated in a well-known manner.

Claim.

What I claim as my invention, and desire to secure by Letters Patent, is—

1. Operating both of the type-wheels G H by their spindle I, in the manner and for the purpose set forth.
2. I also claim the type-wheels G H, provided with notches e, in combination with the spindle I, with its projection f and spring g, operating substantially as and for the purpose set forth.
3. I also claim the type-wheels G H, with the characters marked on their sides, substantially as described, in combination with a casing, E, provided with its holes e d, substantially as and for the purpose set forth.
4. I also claim the key L, or its equivalent, for locking the type-block K in place, substantially as described.

THOS. S. HUDSON.
